UNITED STATES PATENT OFFICE.

HARVEY GILES, OF BROOKLYN, NEW YORK, ASSIGNOR TO ARTEMAS WARD, INC., OF NEW YORK, N. Y., A CORPORATION OF DELAWARE.

VENDING MACHINE.

Application filed January 21, 1926. Serial No. 82,662.

This invention relates to improvements in vending machines and has particular reference to the provision of coin controlled machines for vending packaged merchandise.

5 An important object of my invention is the provision of a coin controlled vending machine with a coin receiving and supporting carriage having adjustable coin supporting means whereby to compensate for wear of the parts and to facilitate control of the machine by coins of different denominations.

10 Another object of my invention is to provide such a machine with means to prevent entrance of a deposited coin to the coin carriage after the column of merchandise has become exhausted and to return such coin to the purchaser.

15 Another object is to provide a coin controlled vending machine with a plurality of 20 columns of like merchandise and a single coin deposit slot for said like columns with means for deflecting the deposited coin from an exhausted column to one having merchandise therein.

25 Another object is to provide such a device which will be simple in construction, strong and durable in service, economical to manufacture and an improvement in the art.

30 With these and other objects in view the invention resides in the novel features of construction, combination and arrangement of parts hereinafter set forth, illustrated in the accompanying drawings and specifically pointed out in the appended claims.

35 In the accompanying drawings wherein a preferred form of the invention is shown in the way of illustration, Figure 1 is a front elevation, partly broken away, of a coin controlled vending machine made in accordance with my invention;

40 Figure 2 is a vertical sectional view on the line 2—2 of Figure 1;

45 Figure 3 is a view similar to Figure 2 showing the several removable sections of the machine ready to be introduced into the casing;

50 Figure 4 is a fragmentary vertical transverse sectional view through the operative mechanism of the device;

55 Figure 5 is a front elevation of the lower portion of the tray for holding the packaged merchandise;

60 Figure 6 is a view similar to Figure 4 taken on the line 6—6 of Figure 11 and showing the lowermost package of one of the columns of merchandise partly displaced;

65 Figure 7 is a view similar to Figure 6 and showing the coin carriage in its extreme rearward position immediately following the release of the lowermost package and the coin;

70 Figure 8 is a vertical longitudinal sectional view on the line 8—8 of Figure 9;

75 Figure 9 is a horizontal sectional view on the line 9—9 of Figure 4 showing the coin carriage and its associated parts in normal position ready to receive an inserted coin;

80 Figure 10 is a view similar to Figure 9 showing the carriage moved to its extreme rearward position;

85 Figure 11 is a horizontal sectional view on the line 11—11 of Figure 4 and showing the coin stop means for preventing the entrance of a coin to the coin carriage after both columns have become exhausted;

90 Figure 12 is a detail elevation of the coin guiding plate;

95 Figure 13 is a detail plan view of the coin carriage per se;

100 Figure 14 is a detail plan view of the coin supporting means which is mounted for movement with the carriage, and

105 Figure 15 is a detail sectional view on the line 15—15 of Figure 10.

110 Similar reference characters designate corresponding parts throughout the several views.

The vending machine illustrated in the drawings comprises a main casing 20 having a back wall 21, side walls 22, top and bottom walls 23 and 24, respectively, and a front wall 25. The front wall 25 includes a lower hinged section designated generally by the reference character 26, and an upper removable section 27, all of these parts being substantially as disclosed in my U. S. Letters Patent No. 1,476,361, issued December 4, 1923, the present case covering improvements on the patented structure.

Within the upper portion of the main casing 20 is a tray 28 in which vertical columns or stacks 29 of merchandise, for example packaged confections, are placed. The tray in the drawings is of suitable proportions to accommodate six stacks of confections, there being three kinds of confections dispensed by the machine, two stacks of each kind being disposed side by side. The lowermost package 30 of each stack 29 is supported by flanges 31, and the rear wall 32 of the tray 28 is cut away at its lower end as shown at 33 to permit the rearward passage of the lowermost pack.

age to the delivery chute 34, in which the package drops by gravity and slides forwardly to the delivery opening 35 below the section 26 of the front wall 25. To insure 5 the progressive downward delivery of the packages, weights 36 are disposed on top of each stack.

The operative mechanism of the machine is located below the tray 28, and is mounted as a 10 unit behind the hinged section 26 of the front wall. It is designated generally by the reference character 36, and includes a stationary frame having side plates 37, connected together at their lower front ends by a plate or bar 38, which forms a guide for the front end 15 of a transverse sliding bar 39 having a handle portion 40 extending through the front wall 26. An offset plate 41 having a horizontal portion 42 connects the plates 37 adjacent 20 their rear edges, and a transverse brace bar 43 extends between the front plate 38 and the rear plate 41, a reinforcing block 44 serving to strengthen the joint between the members 41 and 43, said block also limiting the rearward movement of the sliding bar 39. The 25 transverse brace bar 43 is provided with a longitudinal slot 45 in which a screw 46, carried by the bar 39, travels, whereby to guide the rearward end of the bar 36 in its movement.

A pair of levers 46 are pivoted at 47 to rearwardly disposed ears 48 of the front plate 38, said levers having depending members 49, at their inner ends, in engagement 35 with a pin 50 which projects laterally from each side of the sliding bar 39. Coil springs 51 serve to hold the levers 46, bar 39 and associated parts in their normal position as shown in Fig. 9, each spring having its forward end connected at 52 to one of the levers 46, and its rearward end anchored as at 53 to the horizontal plate 42. The forward extremities of the levers 46 are bifurcated as at 54 for sliding engagement with depending pins 55 carried by forwardly-extending side portions 56 of a horizontal carriage 57 which receives an inserted coin 58 and forces the lowermost package 30 from the corresponding stack 29 as will hereinafter be described. The carriage 57 is preferably formed from sheet metal and includes upper and lower spaced bars 59 and 60 respectively which are slotted as at 61 and connected together by a rear bar 62 and webs 63, the number of slots 61 corresponding to the number of stacks of confections. The outer side edges of the side portions 56 are preferably provided with upwardly and outwardly offset portions 64 (see Fig. 13) which take a bearing in horizontal slots 65 in the side plates 37 to guide the carriage rearwardly in a horizontal position. Mounted with the carriage 57 is a coin supporting member comprising a longitudinal body portion 66, preferably of thicker material than that of the carriage 57, and having

forwardly extending side members 67 adapted to rest upon the side portions 56. Coiled tension springs 68 have their forward ends attached to pins 70 on the members 67, and their rearward ends secured to hooks 71 at the ends 70 of the bar 59. Thus a yielding connection is provided between the carriage and the coin supporting member, guide pins or screws 72 of the members 67 operating in slots 73 of the carriage, and projections 74 on the rear edge 75 of the body portion 66 engaging the inner surface of the bar 62 whereby to limit the relative movement of these parts in one direction. The projections 74 are provided with beveled edges 75 to partially restrict the passage through the slots 61 and to cooperate with the angular fingers 76 in supporting deposited coins in the various slots. The fingers 76 may preferably be made in "rights" and "lefts", one of each being disposed between each pair of projections 74, so that the rearwardly diverging edge 77 of each finger 76 will partially restrict the corresponding slot 61 at the opposite end from the beveled edge 75. Each finger 76 is carried by an enlarged body portion 78 provided with a longitudinal slot 79, through which a screw 80 extends into the body portion 66, and a flange 81 preferably engages the front edge of said body portion 66.

From the foregoing it will be evident that as a coin drops into one of the slots 61 of the carriage 57 it will be stopped and supported in an upright position by engagement with one of the beveled edges 75 and the opposed edge 77 of a finger 76. By virtue of the slot 79 and fastening screw 80, the coin supporting elements 76 may be adjusted relative to the projections 74, whereby to compensate for wear of these parts, or to accommodate 100 coins of various denominations according to the price of the packaged articles in the vending machine. After a coin has been presented to the carriage and the bar 39 drawn forwardly by means of the handle 40, motion is 110 transmitted by the levers 46 to move the carriage 57 and coin holder 66 rearwardly at the same time, and in such movement the coin, being supported in a vertical position as shown in Fig. 6, engages the lowermost package 30 of the corresponding stack and pushes it rearwardly until it passes beyond the influence of the flanges 31, whereupon it falls by gravity into the delivery chute 34 and is presented to the opening 35 from which the purchaser may readily remove it. Simultaneous with the release of the package 30, rearward movement of the coin support 66 is arrested by engagement of its depending pins 82 engaging stops 83, here shown as the edges 115 of apertures in plate 42. Then as the carriage completes the slight remaining portion of its travel, the coin is drawn beyond the support of the members 75 and 76 and it drops down from the slot 61, through an opening 84 120

in plate 42, into a coin receptacle 85 below the operative mechanism. As the handle 40 is released, the parts are returned to their initial positions by the action of the springs 51.

5 In order to control the delivery of the coin, I provide novel and simplified means whereby the coin will be prevented from entering a slot 61 whose corresponding stack of merchandise has become exhausted, and in the 10 event that both stacks of the same kind have been sold out, the coin will be returned to the person depositing it. Referring particularly to Figures 4, 6, 8, 11, and 12, it will be seen that I provide an angularly disposed longitudinal plate 86, having a rearwardly and downwardly inclined portion 87 which terminates in a downwardly extending vertical portion 88. The inclined portion 87 may be provided with ears 89 by which it is loosely 15 pivoted as at 90 to the side plates 37 of the frame 36, the upper edge 91 being disposed immediately below the coin deposit slots 92 as best shown in Fig. 4, and the lower edge of the vertical portion 88 terminating slightly 20 above and in front of the slots 61 when the carriage 57 is in its normal position of rest. A slightly yieldable spring-member 93, carried by the bar 39, engages the front surface 25 of the member 88 to hold it in desired position.

30 Secured to the plates 37 and spaced from the vertical portion 88 of the plate 87 is a vertical plate 94 which, with the portion 88, forms a channel 95 for guiding the coins 35 downwardly in vertical position to the slots 61 of the carriage. The plate 94 is apertured as at 96, the number of apertures preferably corresponding to the number of stacks of merchandise in the tray 28, and disposed in 40 front of said stacks as best shown in Figure 8. Pivot rods 97 extend horizontally across the apertures 96 and support latches 98 in the apertures, there being one latch for each stack. Each latch 98 comprises a rearwardly 45 inclined finger 99 which extends through the corresponding aperture 96 and a similar aperture 100 at the bottom of the front wall 101 of the tray 28 into the downward path of the packages constituting a stack 29, and a forwardly and upwardly extending coin stop member 102. When there is a column of packages in the tray behind a latch 98, the finger 99 is held down so as to raise the member 102 away from the plate 86 and permit 50 passage of a coin to the channel 95. The latches 98 may preferably be arranged in pairs as best shown in Figure 8, one latch member of each pair being for each of the columns of similar merchandise. In this 55 manner after the first column 29 has become exhausted, the corresponding latch member 98 drops into the position shown in dotted lines in Figure 4 so as to prevent passage of the subsequently deposited coins to the slot 61 of the carriage which underlies the ex-

hausted column. Thereafter coins inserted in the corresponding slot 92 will slide downwardly on the inclined plate 87 and be deflected by the coin stop member 102 to a position in the carriage for displacing the lowermost package of the second column. In the event that both columns of like merchandise become exhausted, both of the cooperating latches 98 will drop so that their outer ends 70 102 will rest upon the guide-plate 86 so as to stop the coins as they move downwardly on the plate 87 and prevent their entrance to the channel 95. In such an event as the purchaser pulls the handle No. 40 outwardly to reciprocate the bar 39 and actuate the carriage 57, the spring member 93 is also moved 75 forwardly and the guide-plate 86 swings about its pivot 90 under the influence of gravity to a position shown in Figure 6, whereupon the arrested coin which has been held by the latches 98, as shown in Figure 11, will drop down through the operative mechanism and pass the front side of the receptacle 85 to the bottom of the casing at the opening 35. In this manner positive provision is made 80 for returning coins to purchasers in the event that there is no supply of merchandise in the columns.

85 As the coins are inserted in the slots 92 they slide downwardly upon the inclined portion 87 of the plate 86 and are deflected by angle members 103 so as to pass over detectors 104 which are pivoted at 105 to the plate. The detectors 104 are preferably 90 formed of relatively thin sheet metal and have a weighted body portion 106 which hangs downwardly from the pivot and a projecting point 107 which extends slightly beyond the upper surface of the plate 87 in such a way as to engage and arrest an apertured washer or similar counterfeit which might be inserted in the machine. After the arrest of such a counterfeit, the forward movement of the lower end of the plate 87 will release the counterfeit and return it 100 to the purchaser in a manner similar to the return of a regularly arrested coin. The lower vertical portion 88 of the plate 86 is preferably provided with projecting pins 108 which extend into the channel 95 and guide 105 the coins to their correct positions in the slots 61 of the carriage. In order to permit passage of the vertically supported coins, the stationary plate 94 has its lower edge recessed, as at 109, and the lower front wall 101 of the tray 28 is similarly recessed at 110.

115 In order to prevent tampering with the machine by means of wires or the like inserted through the delivery chute 34, I provide a plurality of closure plates 111 which are pivotally mounted upon a supporting rod 112 extending between the side plates 37 of the stationary frame. Preferably the closure plates 111 are weighted, as at 113, in such a manner that their lower ends 114 will normal- 120 125 130

ly rest against the inclined plate 41 and the arrangement is such that as the machine is operated, the lowermost package 30 as it is ejected from one of the columns is forced 5 against the closure plate 111, swinging the same rearwardly as best shown in Figure 6 so as to permit the passage of the displaced package to the delivery chute 34.

It is thought that the construction of my 10 vending machine will be clear from the foregoing description, and it is to be understood that the drawings are merely illustrative and not presented in a limiting sense, since the invention is susceptible of various modifications. The precise machine illustrated in the drawings is particularly intended for the vending of chewing gum and other confections, but the principles of my invention may be applied with equal advantages to machines 15 for handling other types of merchandise.

In using my invention the various compartments of the tray 28 are supplied with the desired articles to be sold and the operating mechanism 36 and coin receptacle 85 are 20 properly installed below the tray 28 after which the front 25 of the casing 20 is properly applied and locked in place. The operation of the coin supporting carriage in displacing merchandise from the various columns as 25 well as the operation of the coin stop and return mechanisms have already been explained in detail, and such operations will be clearly understood from viewing the drawings with the foregoing explanation. The principal 30 features of the invention reside in the provision of novel means for supporting coins in vertical position in a slidable carriage, said carriage having slots apportioned to the columns of merchandise to be dispensed and particularly characterized by adjustable 35 means for holding the coins in said slots. By providing adjustability for the coin holding means 77, 76, a number of advantages are attained which were not possible with prior 40 art structures. In the first place wear of the parts may be compensated for and furthermore the amount that the coin projects above the coin carriage may be varied in accordance with the thickness of the packages contained 45 in the various columns. Also by such adjustments the machine may be made to accommodate coins of different denominations, if desired, as will be obvious from the drawings.

Another one of the principal features of the invention resides in the coin-stop mechanism by which coins will be prevented from entering the coin carriage in the event that the corresponding column of merchandise has become exhausted and such arrested coins will be returned to the purchaser as the handle of the machine is drawn outwardly to move the carriage. The coin-stop mechanism is particularly simple in construction and is so located that it may be actuated by direct con-

tact with the packages contained within the various columns, and as has been previously pointed out, the coin stop mechanism will be positively held out of the paths of the coins when there is merchandise within the various 70 columns.

The method of supporting the tray 28, operating mechanism 36, and coin receptacle 85 may be similar to the constructions disclosed in my previously mentioned Patent 75 No. 1,476,361 in such a manner than the various units may be readily removed from the casing as shown in Figure 3, when desired.

From the foregoing it will be evident that I have provided an improved vending machine which will be simple in construction and durable in service and embodying the desirable features herein pointed out. The right is herein reserved to make such changes as fall within the scope of the appended claims 85 without departing from the spirit of the invention.

Having thus described my invention, what I claim is:

1. In a vending machine, a main casing 90 having a coin-deposit slot; a tray for supporting a pair of columns of packaged merchandise within the casing; operative mechanism including a carriage for receiving a deposited coin; means for moving the carriage and coin 95 to displace the lowermost package from one of the columns; and coin deflectors pivoted on substantially horizontal axes in front of the columns whereby to deflect the coins to a position in the carriage in line with the 100 second column after the first column has become exhausted, said coin deflectors having portions engageable by merchandise in the respective columns to hold them out of the paths of movement of the inserted coins and 105 which when disengaged due to depletion of the merchandise are actuated by gravity to move into the paths of the coins.

2. In a vending machine, a main casing 110 having a coin-deposit slot; a tray for supporting a pair of columns of packaged merchandise within the casing; operative mechanism including a carriage for receiving a deposited coin; means for moving the carriage and coin 115 to displace the lowermost package from one of the columns; and a pair of latch members pivoted in front of the columns, said latch members having portions engageable by the merchandise in the respective columns to hold them normally out of the paths of the inserted coins, and which when disengaged due to the depletion of the merchandise, are actuated by gravity to move into the paths of the coins, the latch members functioning separately to deflect the coins to a position in the carriage 120 in line with the second column after the first column has become exhausted, and functioning jointly to prevent passage of the coins to the carriage after both columns have become exhausted.

3. In a coin-controlled vending machine having coin-entrance slots, a tray for holding vertical columns of merchandise to be sold, an exposed operating handle, a horizontally 5 slidable carriage operable from said handle, said carriage having vertical coin slots apportioned to the columns, a transverse bar mounted on the carriage and provided with projections crossing the coin slots to support 10 coins on edge in the slots, means for varying the distance between the projections of each slot, means for arresting said bar at a predetermined point during the operative movement of said carriage and before said movement has ceased whereby said vertical slots 15 are carried beyond the projections to release the coins, and springs connecting said bar and carriage whereby to restore the normal relation of the bar and carriage on the reverse 20 movement of the carriage.

4. In a coin-controlled vending machine having coin-entrance slots, a tray for holding vertical columns of merchandise to be sold, an exposed operating handle, a horizontally 25 slidable carriage operable from said handle, said carriage having vertical coin slots apportioned to the columns, a transverse bar mounted on the carriage and provided with spaced integral projections crossing one end 30 of each coin slot and adjustable projections crossing the other end of each coin slot, said projections being adapted to support coins on edge in the coin slots and the adjustable projections permitting variation of the distance 35 between each pair of co-operating projections, means for arresting said bar at a predetermined point during the operative movement of said carriage and before said movement has ceased whereby said vertical 40 slots are carried beyond the projections to release the coins, and springs connecting said bar and carriage whereby to restore the normal relation of the bar and carriage on the reverse 45 movement of the carriage.

5. In a coin-controlled vending machine having coin-entrance slots, a tray for holding vertical columns of merchandise to be sold, an exposed operating handle, a horizontally 50 slidable carriage operable from said handle, said carriage having vertical coin slots apportioned to the columns, a transverse bar mounted on the carriage and provided with spaced integral projections crossing one end of each 55 coin slot, adjustable fingers carried by the transverse bar and extending into the coin slots, each finger co-operating with one of the integral projections to support a coin vertically in one of the slots, whereby the coin will engage and displace the lowermost package 60 from the corresponding column in the tray when the carriage is actuated, means for arresting said bar at a predetermined point during the operative movement of said carriage after said lowermost package has been displaced, whereby the vertical slots are carried 65 beyond the projections and fingers to release the coins, and means for restoring the normal relation of the bar and carriage on the reverse movement of the carriage.

6. In a coin-controlled vending machine, 70 the combination with a casing having coin entrance openings, and a tray for supporting vertical columns of merchandise to be sold, of operative mechanism including a carriage transversely slidable below the columns, said carriage being formed of sheet material and having a pair of spaced horizontal portions provided with aligned vertical coin slots, and coin supporting members arranged in pairs between the horizontal portions, each pair 75 restricting the passage through one of the coin slots to support a coin vertically therein, and one member of each pair being adjustable to vary the separation of the pair, a handle projecting through the casing, means for sliding the carriage by operation of the handle to displace one of the packages of merchandise from the column, means for releasing the coin from the coin supporting members after displacement of said package, and springs 80 for returning the parts to normal position.

7. In a coin-controlled vending machine, the combination with a casing having coin entrance openings, and a tray for supporting vertical columns of merchandise to be sold, 85 of operative mechanism including a carriage transversely slidable below the columns, said carriage having vertical coin slots apportioned to the columns and adjustable coin supports restricting the passage of coins through said slots, a handle extending through the casing for actuating the carriage, coin-guiding means including an inclined plate and a narrow vertical passageway for directing inserted coins from the coin entrance openings to the coin slots of the carriage, and coin-stop means adapted to arrest coins and prevent their entrance to a coin slot 90 after the corresponding column of merchandise has become exhausted, said coin-stop means including latches pivoted at the top of the vertical passageway and having portions adapted to lie against the inclined plate in the path of the coins when the column is empty, and a finger directly engaged by the merchandise to control the position of the latches, and means for simultaneously moving the carriage rearwardly and tilting the inclined plate downwardly, substantially as set forth.

8. In a vending machine a main casing having a coin-deposit slot, a tray for supporting a column of packaged merchandise within the casing, and operative mechanism for receiving a deposited coin and for moving it 100 against the lowermost package of the column to displace said package, said mechanism including a reciprocatable carriage for maintaining the coin in operative position, a reciprocatable bar having a handle at its for- 105

110

135

ward end projecting from the casing, connecting means between the carriage and said bar, and a supporting frame for said carriage and bar, said frame including spaced parallel side plates rigidly connected together by front and back longitudinal plates, a transverse brace member extending between said front and back plates intermediate their ends,

and a reinforcing block providing a substantial connection between the rear plate and the transverse brace, said reinforcing block being disposed in the path of rearward movement of the reciprocatable bar and functioning as a solid abutment therefor.

HARVEY GILES.
